AIR CONDITIONER

Harry D. Betz, Kansas City, Mo.

Application September 18, 1931
Serial No. 563,498

8 Claims. (Cl. 62—133)

This invention relates to improvements in air conditioners and more particularly to an air cooler and conditioner of the portable type using ice cooled water as the air cooling agent.

5 My device is particularly adapted for use in homes, offices, hospitals, hotel rooms and other places where the cost of installing a permanent air cooling and conditioning apparatus would be too expensive for the average householder or 10 where the construction of a building is such that a permanent installation would not be desirable, and, since it is designed primarily for employing ice as the cooling medium, no complicated expensive mechanical refrigerating device is required; therefore, a considerable reduction in the 15 cost of manufacture as well as mechanical maintenance is achieved.

I am aware that air has been cooled by blowing it over cakes of ice but in such cases the 20 humidity of the air was increased and the air had very little if any dust odors or smoke removed therefrom, but by the use of my device the air is not only cooled by sprays of cold water, it is also washed and dehumidified, by causing 25 the air to pass through a fine spray of water whose temperature is below the dew point of the incoming air. Obviously, in an air conditioning plant, it is not only necessary to cool the air in summer, but likewise essential to wash and reduce the humidity of such air.

30 My device can also be used to humidify relatively dry air by using warm, instead of chilled, water for washing it, in which case my air cooler and conditioner not only cleanses the air but 35 also permits the air to absorb moisture from the spray, thus restoring the moisture which has been removed from the air by action of the heating apparatus. The humidification of air is not only desirable as a matter of comfort, but also from 40 a hygienic standpoint and in the preservation of furniture and other articles to which dry heat is injurious.

In the drawing:

Fig. 1 is a vertical, longitudinal, sectional view 45 of my device taken on the line 1—1 of Fig. 2.

Fig. 2 is a vertical cross section taken on the line 2—2 of Fig. 1.

Fig. 3 is a horizontal section taken on the line 3—3 of Fig. 2.

50 Referring to the drawing:

1 indicates a reservoir adapted to receive cakes of ice and water and having a top 2, a bottom 3, side walls 4 and end walls 5, all of which are preferably of double construction and contain insulating material 6. To the bottom 3 are prefer-

ably affixed wheels or casters 7 which permit the device to be readily movable.

The top 2 is provided with a closure 8 serving as a charging opening for the ice and water and is normally covered with a lid or door 9 in which a grilled panel 10 is preferably located. While this panel is preferably hinged to the top it may be made entirely removable if desired.

The top 2 is further provided with an opening 11 in which a closure 12 may be fitted. A tubular member 13 passes vertically through said opening or closure and has a suitable pump 14 secured to its lower end which is attached to a conduit 15. A drive shaft 16 extends through the tubular member 13 and has its upper end 70 secured to a motor 17 which is mounted on the upper end of the tubular member and above the top 2 of the reservoir 1.

The top 2 is further provided with an opening 18 and preferably adjacent one side and end 75 wall of the reservoir 1. This opening is surrounded by an upwardly extending housing 19 preferably having inner and outer walls insulated apart by a suitable insulating material 19a.

Connected to the pump conduit 15, by means 80 of a coupling 20, is a conduit 21 which extends upwardly within the housing 19 and terminates in a header pipe 22 which carries spray nozzles or sprinkler heads 23.

Located above the nozzles 23 are a plurality 85 of corrugated moisture eliminator plates 24 which extend entirely across the inner housing for the purpose of preventing entrained moisture from passing upward and outwardly from the conditioner with the current of air.

The upper portion of the housing 19 is preferably provided with a hood 25, in which a motor driven fan 26 is located for the purpose of drawing air, which it is desired to condition, from the room, and into the cooler and air conditioner 95 through the grilled panel 10 and upward through the insulated housing 19, past the moisture eliminator plates 24 and then discharge it from the hood into the room.

An ornate grille 29 is preferably secured at the 100 front of the hood 25 behind which I preferably use deflectors 30 so arranged as to give an upward pitch to the air as it leaves the air conditioner, and also for the purpose of straightening out the air currents, thus eliminating the turbulent currents that would otherwise result due to the rotation of the fan.

The pipe 28 is provided with a three way valve 31 which has a valve stem 32 projecting through the housing 19 and is provided with a hand 110

wheel 33 at the exterior of the housing 19 for manipulating the valve. A normally closed pipe 34 is attached to one terminal of the valve 31. This pipe is preferably threaded on its outer end 5 in order to provide a connection for a hose or conduit.

The purpose of this valve and pipe is to provide a means whereby the pump 14 can pump out a sufficient quantity of water from the reservoir for 10 recharging it with ice. A drain 27 is provided in the bottom of the reservoir for complete draining.

The water issuing forth from the spray nozzles 23 is directed outwardly and downwardly at 15 the same time producing a fine mist within the housing. However, a part of the spray strikes the side walls and thence trickles down the same. Therefore, in order to eliminate the disagreeable noise that would result if this water were allowed to drip into the body of water in the reservoir, I have provided an inwardly projecting trough 35 extending completely around the lower 20 end of the inner wall of the housing 19 for the purpose of catching the water moving down such side walls and deliver it to the body of water 25 in the reservoir through a pipe 36, which terminates at a point below the normal water level. The inclination of this trough also permits moisture which has condensed on the outside of the 30 trough to trickle down while adhering to the under side thereof and reach the pipe 36 and thence run down the outer surface to the water in the reservoir 1, instead of permitting it to drip off and splash, hence this greatly assists 35 in ridding my air conditioner of noises during its operation.

A vertical baffle plate 37 extends longitudinally of the reservoir and is made practically watertight at one end and at the bottom thereof. The 40 end furthest from the pump end of the reservoir is spaced from the end wall in order to permit passage of water around its end.

This baffle is primarily for the purpose of compelling complete circulation of the water from 45 the discharge pipe 36 leading from the upper housing 19 around the end of the baffle to the pump intake, which is obviously on the opposite side of the baffle. This water circulation is made to travel practically uniformly over the 50 side surfaces of all submerged ice and, therefore, makes possible a greater reduction in water temperature at the pump than would be possible if it were not for the baffle 37. Further 55 the baffle is advantageous for the purpose of guiding the cakes of ice and preventing diagonal positioning resulting in lessening the ice capacity of the reservoir.

Having described my present invention in one form, I do not desire to be restricted to this 60 particular detail arrangement, that is, such as mounting the reservoir on casters and the like, it being understood that other arrangements of elements could be made without changing their functional purposes as herein set forth.

65 What I claim and desire to secure by Letters Patent is:

1. A self-contained air conditioner comprising a reservoir having an air inlet opening in its top and adapted to contain a liquid cooling agent 70 and ice for cooling said liquid, an upwardly extending housing carried by said reservoir, means located within said housing for spraying the cooling agent downwardly within the housing, means in the housing for collecting the spray to prevent 75 it from dripping onto the ice in the reservoir, and

means for drawing air upward through said spray and discharging it from said housing.

2. A self-contained air conditioner comprising a reservoir having wheel supports and adapted to contain a liquid and ice for cooling said liquid, an air inlet formed in said reservoir arranged to admit air to be conditioned at a point above the ice, a housing extending upwardly from said reservoir and communicating with the interior thereof, means located within said housing for spraying said cooling agent downwardly, and means located in said housing and above said spraying means for drawing the air from the reservoir and through said liquid sprays and discharging the same from the upper part of said housing.

3. A self-contained air conditioner comprising a reservoir adapted to contain a cooling agent and having an air inlet arranged to admit air over the top of said cooling agent, an air shaft communicating with the interior of said reservoir and extending upwardly above the reservoir, means for spraying said cooling agent downwardly in said air shaft, means adjacent the bottom of the shaft for catching the main portion of said sprayed cooling agent and delivering it through a restricted path to a point below the surface of said cooling agent to prevent the spray from dripping onto the surface of said cooling agent, and means for moving air through said sprayed liquid and discharging the same from said air shaft.

4. In a self-contained air conditioner comprising a reservoir designed for using ice as the cooling medium, a baffle plate in the reservoir, a vertical housing supported above the reservoir, an air washer including spray nozzles and moisture 100 eliminator plates located in the vertical housing, a pump for delivering liquid resulting from the melted ice to said washer nozzles, means located in the bottom of the housing to catch the spray delivered from said nozzles for return to the reservoir to prevent the spray from dripping over the ice, and a fan for circulating air through the washer.

5. An air conditioner comprising a reservoir adapted to contain a liquid and means for chilling the same, an air shaft carried by said reservoir, a conduit located within said air shaft, spray nozzles carried by the upper end of said conduit, means for delivering the liquid to said conduit and nozzles, a trough adjacent the lower end of said shaft to catch the liquid from said spray, a pipe communicating with the trough for delivering the liquid to the reservoir to prevent the spray dripping onto said chilling means, and means for moving air upwardly in said air shaft and discharging the same therefrom above said nozzles.

6. A device of the character described comprising a reservoir adapted to contain a liquid cooling agent and having an opening at its top for inserting ice to cool said liquid agent and for admitting air to the reservoir over the top of said ice, a vertical housing supported by the reservoir adjacent said opening and having its lower end communicating with the reservoir, means in the top of the housing for drawing air through said inlet and upwardly in the housing, a series of spray nozzles located in the housing and arranged to direct the cooling agent against walls of the housing across the path of the air, means for pumping the cooling agent from the reservoir to said nozzles, a trough extending around the walls of the housing adjacent its lower end to catch the cooling agent, and a conduit connected with said trough for returning the liquid to the

reservoir for preventing the liquid from dripping onto the ice and the surface of the cooling liquid in the reservoir.

7. An air conditioner comprising a reservoir adapted to contain a cooling liquid and means for cooling the liquid, an upwardly extending air shaft on the reservoir, means for circulating the liquid in the reservoir including means for spraying said liquid downwardly in the air shaft, a vertically positioned baffle in the reservoir for directing the circulating liquid around said cooling means, and a fan for moving air upwardly through said sprayed liquid and discharging said air from the upper end of the air shaft.

15 8. An air conditioner including a reservoir

adapted to contain a liquid cooling agent and means for cooling said liquid, a vertically positioned baffle substantially dividing said reservoir and having one end spaced from an adjacent wall of the reservoir to allow flow of the liquid cooling agent from one side of the baffle to the other, a housing extending upwardly from the reservoir and communicating with the interior thereof, means for removing liquid from one side of the baffle and spraying it into said housing for downward flow into the reservoir on the opposite side of the baffle, and means for moving air upwardly through said spray and out of the housing.
